United States Patent

Des. 240,584
Patented July 20, 1976

240,584

SHELF UNIT OR SIMILAR ARTICLE

John McGrann, 5851A Lincoln,
Morton Grove, Ill. 60053

Filed Nov. 16, 1973, Ser. No. 416,634

Term of patent 14 years

FIG. 1.

FIG. 3.

FIG. 2.

FIG. 4.

FIG. 5

FIG. 1 is a perspective view of a shelf unit or similar article embodying my new design;

FIG. 2 is a side elevational view thereof;

FIG. 3 is a front elevational view thereof;

FIG. 4 is a rear elevational view thereof; and

FIG. 5 is a top plan view thereof.

I claim:

The ornamental design for a shelf unit or similar article, substantially as shown.
